UNITED STATES PATENT OFFICE.

GURDON P. JUDSON, OF FAIRFIELD, IOWA.

WELL SEAL.

Application filed April 22, 1924. Serial No. 708,219.

To all whom it may concern:

Be it known that I, GURDON P. JUDSON, a citizen of the United States, residing at Fairfield, in the county of Jefferson and 5 State of Iowa, have invented certain new and useful Improvements in Well Seals, of which the following is a specification.

This invention relates to well seals and more particularly to a seal for irrigation wells. It has heretofore been the practice to seal irrigation wells by wrapping sacks about the well casing and suction pipe at the point of entrance of the suction pipe into the casing, but this has proven unsatisfactory inasmuch as it has been found that the well must be resealed several times in a season. Therefore, the present invention has as one of its objects to provide a seal which may be applied to the suction pipe of an irrigation well and, when the said pipe is lowered into proper position within the upper end of the well, will automatically seal the well and obviate the cumbersome procedure of sealing the well in the ordinary manner. 25 Another object of the invention is to provide a seal so constructed that it may be caused to more or less firmly bind the suction pipe and yet in a manner to permit of sliding movement of the pipe through the seal so that the seal will be automatically adjusted with relation to the pipe when the pipe is inserted into the top of the well.

Another object of the invention is to provide a seal which will be extremely simple in construction, inexpensive to manufacture, and not liable to require attention or repairs after it has been once installed, and which seal will be durable and air and fluid tight.

In the accompanying drawing:

40 Figure 1 is a view in elevation of the seal embodying the present invention installed, the well casing being shown in section as also the upper portion of the well;

45 Figure 2 is a detail vertical diametric sectional view taken substantially on the line 2-2 of Figure 1 looking in the direction indicated by the arrows, the suction pipe being shown in elevation;

50 Figure 3 is a horizontal sectional view taken substantially on the line 3-3 of Figure 1 looking in the direction indicated by the arrows.

In the drawing, the numeral 1 indicates the well pit and the numeral 2 indicates the well casing, the upper end of the casing projecting into the pit a short distance above the bottom thereof, as is usual. The numeral 3 indicates the suction pipe of the pump and the numeral 4 indicates the delivery pipe which is in communication with the 55 said suction pipe 3 in the usual manner, the water in the well casing being elevated through the suction pipe by means of an ordinary centrifugal pump 5 operated through the medium of a shaft 6, pulley 7, and belt 8 60 housed within a structure 9 mounted upon the base 10 of the well.

The seal embodying the present invention is indicated in general by the numeral 11 and the same comprises a substantially cylindrical body 12 which may be made of rubber, a composition of rubber and fabric, or of any other suitable material or combination of materials either with or without reinforcements, the only requirement being 75 that the material shall be more or less yieldable and substantially water-proof. The body is provided with an axial bore 13 which is of a diameter to slidably fit the suction pipe 3 of the well pumping apparatus, 80 and exteriorly the body is formed at its upper end with a circumscribing shoulder 14 and at its lower end with a similar shoulder indicated by the numeral 15. The under side of the seal body 12 is plane as indicated 85 by the numeral 16 and is designed to engage and rest squarely upon the upper end of the well casing 2 as clearly shown in Figures 1 and 2 of the drawings. The upper surface of the shoulder 15 is preferably rounded 90 from its juncture with the intermediate portion of the body 12, to the periphery of the shoulder as indicated by the numeral 17.

In order that the seal body 12 may be caused to more or less firmly embrace the 95 suction pipe 3, a clamping means comprising two semi-annular collar sections 18, is provided, and each of these collar sections is formed at its ends with outstanding ears 19 having openings 20 therein for the passage 100 of clamping bolts indicated by the numeral 21. The collar sections 18 embrace the intermediate or thinner portion of the body 12 as clearly shown in Figures 1 and 2 of the

drawings, and by tightening the bolts 21, the sections may, as stated, be caused to more or less firmly bind this portion of the body 12 about the suction pipe 3.

- 5 In order that resistance may be offered to any upward distortion of the shoulder 15 when the seal body is lowered to position bearing upon the upper end of the well casing 2, the collar sections 18 are formed each 10 with a circumferential outstanding flange 22 extending about its lower edge and transversely curved to conform to the transverse curvature of the upper surface 17 of the said shoulder 15. These flanges are so formed as 15 to provide projecting end portions 23 located beyond the ends of the collar sections proper 18, and in the assembled relationship of the parts the said projecting end portions 23 of the flanges of the two collar sections overlap 20 as best illustrated in Figures 2 and 3 of the drawings so that a backing, so to speak, is provided for the entire area of the upper face of the said shoulder 15.

In applying the seal to the suction pipe 3, 25 the bolts 21 are loosened and the seal body 12 is slipped onto the pipe and adjusted to a position where it will strike, at its under side, against the upper end of the well casing 2 when the suction tube is fully introduced to proper position within the well casing. The bolts 21 are then tightened to cause the said member 12 to frictionally bind the suction pipe 3 to a greater or less degree, and the said suction pipe is then lowered into the 30 well casing 2. When the under side of the shoulder 15 meets the upper end of the well casing 2, the seal having been properly adjusted as previously explained, the base 10 will be positioned a greater or less distance 35 above the ground surface or the well curbing. Downward pressure is then exerted until the base 10 seats upon the curbing or ground surface, and in this downward movement of the structure including the suction pipe 3, the said pipe will be slid downwardly 40 through the bore 13 of the seal body 12. In this manner the well is effectually sealed in an air and fluid tight manner. It will be evident that the shoulder 15 is reinforced so 45 as to prevent it becoming distorted or deflected in an upward direction, by reason of the engagement of the flanges 22 against its upper side. It will likewise be evident that the clamping means comprising the collar sections 18 is prevented from displacement 50 with relation to the seal body 12, due to the disposition of the collar sections between the shoulders 14 and 15.

It will be observed from the drawings that 60 the under side of the seal is flat and that due to this fact, there is no likelihood of the seal being forced into the well casing 3, as is the case in other types of seals, and which would result in sticking of the seal or splitting of 65 the top of the casing.

Having thus described the invention, what is claimed as new is:

1. A well seal comprising a body of yieldable material having a pipe receiving bore and provided at its lower end with a bearing surface, and clamping means embracing the said body. 70

2. A well seal comprising a body of yieldable material having a pipe receiving bore, circumferential shoulders at the upper and lower ends of the body, the face of one shoulder constituting a bearing surface for engagement with the end of a well casing, and clamping means embracing the said body between the shoulders. 75

3. A well seal comprising a body of yieldable material having a pipe receiving bore, the body being provided at its lower end with a circumscribing shoulder having a seating under face to engage the end of a well casing, clamping means embracing the said body above the shoulder, and means associated with the clamping means and resting upon the upper side of the shoulder to prevent upward deflection of the said shoulder. 80

4. A well seal comprising a body of yieldable material having a pipe receiving bore and provided at its lower end with a circumscribing shoulder the under face of which constitutes a bearing surface for engagement with the end of a well casing, and a clamping collar fitted about the said body above the shoulder and having an outstanding flange extending over and bearing upon the upper side of the said shoulder. 95

5. A well seal comprising a body of yieldable material having a pipe receiving bore and provided at its lower end with a circumscribing shoulder the underside of which constitutes a bearing surface for engagement with the end of a well casing, a two part collar disposed to circumscribe the body above the said shoulder, means for drawing together the ends of the said collar parts whereby to cause the parts to bind about the body and effect frictional binding of the wall of the bore about the pipe to which the seal is fitted. 105

6. A well seal comprising a body of yieldable material having a pipe receiving bore and provided at its lower end with a circumscribing shoulder the underside of which constitutes a bearing surface for engagement with the end of a well casing, a two part collar disposed to circumscribe the body above the said shoulder, means for drawing together the ends of the said collar parts whereby to cause the parts to bind about the body and effect frictional binding of the wall of the bore about the pipe to which the seal is fitted, the said collar parts being provided with outstanding flanges at their lower edges engaging the upper side of the said shoulder. 110

7. A well seal comprising a body of yieldable material having a pipe receiving bore and provided at its lower end with a circumscribing shoulder the underside of which 5 constitutes a bearing surface for engagement with the end of a well casing, a two part collar disposed to circumscribe the body above the said shoulder, means for drawing together the ends of the said collar parts 10 whereby to cause the parts to bind about the

body and effect frictional binding of the wall of the bore about the pipe to which the seal is fitted, the said collar parts being provided with outstanding flanges at their lower edges engaging the upper side of the 15 said shoulder, and having their ends mutually overlapped.

In testimony whereof I affix my signature.

GURDON P. JUDSON. [L. s.]
